UNITED STATES PATENT OFFICE

145,590

DESIGN FOR A CASING OR BODY FOR A LIGHTER OR THE LIKE

Leo Soklaski, Brooklyn, N. Y.

Application January 17, 1946, Serial No. 125,672

Term of patent 14 years

(CL. D48—27)

To all whom it may concern:

Be it known that I, Leo Soklaski, a citizen of the United States, residing at Brooklyn, in the county of Kings, in the city and State of New York, have invented a new, original, and ornamental Design for a Casing or Body for a Lighter or the Like, of which the following is a specification, reference being had to the accompanying drawing, forming part hereof.

In the drawing,

Fig. 1 is a perspective view of a casing or body for a lighter or the like showing my new design; Fig. 2 is a front elevation thereof; and Fig. 3 is a top plan view of the same.

I claim:

The ornamental design for a casing or body for a lighter or the like, substantially as shown.

LEO SOKLASKI.
